CLAIM

The ornamental design for an automobile trailer, as shown and described.

DESCRIPTION

FIG. 1 is a right side elevation view of an automobile trailer showing my new design, it being understood that the broken lines are for illustrative purposes only and form no part of the claimed design, the left side being a mirror image thereof:

FIG. 2 is a rear elevation view thereof;

FIG. 3 is a front elevation view thereof;

FIG. 4 is a top plan view thereof;

FIG. 5 is a bottom plan view thereof;

FIG. 6 is a side elevation view thereof, with the front portion thereof in extended condition on a reduced scale, and,

FIG. 7 is a top plan view of FIG. 6.

FIG. 1

*FIG. 2**FIG. 3*

FIG. 4

FIG. 5

FIG. 6

FIG. 7
